INVENTOR
CARL P. BROCKWAY
BY
Chester A. Brasell
ATTORNEY

UNITED STATES PATENT OFFICE

CARL P. BROCKWAY, OF PATERSON, NEW JERSEY, ASSIGNOR, BY MESNE ASSIGNMENTS, TO THE TILLOTSON MANUFACTURING COMPANY, OF TOLEDO, OHIO, A CORPORATION OF DELAWARE

MUFFLER

Original application filed July 27, 1921, Serial No. 487,974. Divided and this application filed March 17, 1927. Serial No. 176,261.

This invention relates to internal combustion engines, and more particularly to a muffler adapted to be used in conjunction therewith and is a divisional application of my prior application entitled, "Two cycle 5 rotary plant", Serial Number 487,974, filed July 27, 1921.

One of the objects of the invention is to provide a muffler having internal absorbing fins and external radiating fins; another 10 object is to provide a muffler with heat absorbing fins adapted to form expansion chambers one with the other.

Further objects and objects relating to 15 economies of manufacture and details of construction will become apparent as the description of the invention proceeds.

A preferred embodiment of the invention 20 is illustrated in the accompanying drawings wherein

Figure I is a vertical section of a combined 25 rotary engine and dynamo unit with the improved muffler connected thereto, taken through the shafting; and

Figure II is a section through the engine 30 along lines II—II of Figure I;

Referring to Figure I the combined power 35 unit is shown as including a rotary engine 10 and a dynamo electric machine 11 both of which are interconnected and in axial alignment; the engine having support through the stationary crank shaft 12, bearing 13, standard 14, and the dynamo having support through the bearing 14', and standard 15 upon the common base 16.

The engine is rotatably mounted through 40 the bushing 17 upon the stationary crank shaft 12 which extends into the crank case 18 of the engine. The crank shaft carries on the crank end the crank arm 19 to which, by means of the screw 20, the roller bearing 21 of the connecting rod head 22 is attached.

The connecting rod 23 is rotatably mounted 45 on the wrist pin 24 which pin has a pivoted bearing in the skirt 25 of the piston 26 so that rotation of the engine about the fixed crank shaft bearing will, by reason of the offset crank arm pivot 21, cause reciprocation of the piston in the explosion chamber 27.

The engine is of the two cycle type and has

an intake passage 28 which communicates with an inlet port 29 in the crank case so positioned that when the piston is in its upper position the port is exposed to the crank case interior permitting inflow of fuel gases. A 55 conduit 30 is formed in the cylinder wall 31 having a lower and upper outlet so positioned that when the piston is in its lowermost position the lower outlet registers with the port 32 cut in the piston skirt 25 and the upper 60 outlet opens into the explosion chamber 27 above the piston head 33. It is apparent therefore, that when the piston is in its lowermost position unburned gas is entering the explosion chamber from the crank case 65 through conduit 30. A deflector 34 of conventional design is utilized to give the incoming gas an upward movement.

The outlet or exhaust ports 35 are so placed 70 in the engine wall that when the piston is at its lowermost position the ports are completely uncovered as indicated in Fig. I. A pipe 36 conducts the expelled gases to the muffler 37 which will now be described.

The muffler 37 is designed to form a counter 75 weight for the engine cylinder 31 and enclosed piston 26. For this purpose the muffler cylinder 38 is formed as an extension of the engine crank case 18 and is positioned on the side of the engine axis opposite the engine member. The muffler has a mass approaching 80 in value that of the engine member and includes in addition to the cylindrical wall 38, a head 39 to which is integrally secured an inwardly projecting central post 40 having 85 outwardly and laterally extending partition plates 41 fixed thereto at approximately regular intervals. An outwardly projecting plate 42 extends from the closed inner end 43 of the muffler to a point adjacent the 90 muffler cylinder head 39 thus dividing the muffler cylinder radially into a larger chamber 44 and smaller chamber 45 connected by a passageway 46. The chamber 44 is preferably 95 cylindrical in transverse section and the plates 41 conform in outline to the interior of the chamber, their edges approaching the chamber wall but terminating at a distance therefrom so that an annular passageway 47 around each plate is formed. In addition 100

passages 48 are cut in the various plates at points which do not register radially in successive plates. The exhaust pipe 36 connects with a port 49 opening into the inner end 5 of the muffler chamber 44.

The gas mixing and intake chambers and valves are positioned in and adjacent the crank shaft member. For a portion of its length exterior to the engine crank case and 10 within the bearing 13, the crank shaft 12 is hollowed, the inner end of the hollowed portion 50 connecting with the intake conduit 28 and the outer end opening into exterior ports 51 cut into a cap 52.

15 The chamber 45 extends radially toward the engine shaft and is then offset axially as at 81 terminating in an annular U-shaped channel 82, opening outwardly and axially from the engine. The channel 82 registers 20 with a similar U-shaped channel 83 fixed to the bearing 13, the edges of the channels being adjacent, the inner edges contacting and the outer edges 83' being sufficiently separated to form a non-frictional joint thereby 25 permitting passage of gases therethrough. In the channel 83 the stationary exhaust port 84 is formed to which the exhaust pipe may be secured.

30 The exhaust gases are cooled by conduction and radiation from transverse fins 87 formed integrally with the walls of the muffler cylinder. In addition the heated gases expand into the muffler chambers 44 contacting with the partition surfaces 41 releasing heat there- 35 to which in turn is conducted to the muffler head and radiated.

In order to prevent largely the escape of 40 gases from the muffler into the atmosphere immediately about the engine through the open joint between the rotary and stationary parts of the engine, utilization is made of the air pressure developed through the rotation of the engine unit in a drum shaped casing 88 which communicates, by means of a conduit 89 in the base, with the hollow standard 14. From the standard 14 an annular channel 90 leads around the exhaust channel 83 and the loose joint 83' between the registering channels 82 and 83, the inner edge 91 of 45 the channel 90 having a close but small frictional bearing on the channel member 82.

It is apparent that the air pressure developed in the engine casing is transmitted to the annular joint 83' thus tending to prevent egress of exhaust gases at this point and thus making possible a noncontacting joint between the heated rotating member and non-rotating channel member 82 and 83. Further, the air pressure developed forces 50 some air through the joint 83' which air being relatively cool and mixing with the exhaust gases, tends to diminish the temperature of the same thereby preventing excess heat at the rotating bearing 17. It 55 should also be noted that the passage of the

heated exhaust gases about the intake chamber heats the same thereby permitting ready combustion of the intake gases.

Subsequent to explosion the exhaust gases 70 pass into the muffler wherein after successive expansion the gas is expelled through the annular channel 83 about the intake and out the exhaust port 84.

It is evident that many modifications of the embodiment illustrated and described 75 may be resorted to without departing from the spirit of the invention and I do not therefore desire to limit myself to the specific embodiment shown and described, but to interpret the invention broadly limited 80 only by the following claims:

Having thus described my invention, what I claim is:

1. A muffler for gas engines comprising in combination, a casing having external heat radiating fins; a partition separating the casing into two compartments; a removable head for said casing; a plurality of conically shaped baffle plates in one of said compartments, said removable head forming a support for said baffle plates; and a passageway between said compartments whereby the exhaust gases flow in opposite directions through said compartments. 85

2. A muffler for gas engines comprising in combination, a casing; a partition separating the casing into two compartments; a plurality of conically shaped baffle plates positioned in one of said compartments and having non-registering peripheral notches 90 in said plates; a communicating passageway between said compartments whereby the exhaust gases flow in opposite directions through said compartments. 95

3. In a muffler for use in rotary gas engines, a relatively movable casing formed with two compartments; a removable head for said chamber; a plurality of conically shaped baffle plates integrally formed in said head and extending into one of said compartments; a communicating passageway between said compartments so arranged that exhaust gases flow in opposite directions through said compartments. 105

In testimony whereof, I affix my signature. 115
CARL P. BROCKWAY.
